Walter W. White, ³⁴ Inventor:

Errett Dufour, Attorney.

UNITED STATES PATENT OFFICE.

WALTER W. WHITE 3. W., OF DENVER, COLORADO.

TOY.

1,342,037.

Specification of Letters Patent.

Patented June 1, 1920.

Application filed October 17, 1918. Serial No. 258,607.

To all whom it may concern:

Be it known that I, WALTER W. WHITE 3. W., citizen of the United States, residing at Denver, in the county of Denver and State 5 of Colorado, have invented certain new and useful Improvements in Toys, of which the following is a specification.

This invention relates to improvements in toys or devices particularly of that type de- 10 signed to aid the "tots" or little ones, in their efforts to walk, by intuition or instinct.

The invention has for its object to stimulate or excite in the child the effort to walk by observing or beholding the movements or 15 action of the device as will be more fully disclosed farther on.

A further object is to provide for carrying out the aforesaid end, together with accomplishing other useful purposes, in a sim- 20 ple, inexpensive and effective manner, and with facility.

The invention consists therefore of certain instrumentalities and features of construction substantially as hereinafter more fully 25 disclosed and defined by the appended claim.

In the accompanying drawing is illustrated the preferred embodiment of my invention wherein it will be understood that various changes and modifications as to the 30 detailed construction and arrangement of parts may be made without departing from the spirit or scope of the claim, and in which drawing,—

Figure 1 is a side elevational view of my 35 improved toy or device.

Fig. 2 is a front elevational view thereof.

In carrying out my invention I suitably mount upon a cranked shaft or axle 1 carried by a pair of wheels 2, a suitable figure 3, such as the effigy or representation of a human being, and which, as in the example shown, preferably should be in an attractive or grotesque form in order to draw the attention of a child, for the reasons given. The cranked shaft or axle 1, which is fast to the wheels 2, is preferably extended at its ends as at 1^a, the resultant extensions 1^a thereof, however, projecting eccentrically from the wheels and having 45 connection with like extensions 4^a of a second like cranked shaft 4^b by means of push or connecting rods 5. The base-member 6 has passing therethrough and suitably seated therein, as at 7, the cranked shaft or axle 1, 50 1. To the upper edges of said base-member is suitably secured the bottom-supporting

member 8 of standards 9 in whose upper ends is seated the cranked shaft 4. The assembling and securing together of these several parts may be carried out in any suitable 60 way, as the invention does not lie in any particular therein.

The effigy or figure 3, which is formed of a shell of sheet-metal or the like, has arranged in connection therewith a preferably 65 rectangular frame 11, to which, at its upper end, is suitably pivoted a bail-like member 12, having pivoted or articulated thereto a like member 13. Suitably connected to an extension or stem 14 projecting from the 70 member 12, is the head of the figure or leg- end, so positioned, however, as to be in requisite juxtaposition to the body-portion of the figure. These members, thus freely jointed together, one of which has cast there- 75 with simulated human-hands 15 fixedly grasping the crank-shaft 4, provide for allowing of the usual flexing action of the arms. The lower end of the frame 11 has similarly pivoted thereto a bail-like member 80 16 and the latter has articulated thereto a like member 17 having cast therewith simulated human feet 18, whereby a flexing action between said members and their points of connection with said frame is provided 85 for, simulating the action of the human legs. Suitable means are provided in the form of a handle or bar 19 adaptable for insertion into a tubular member or socket 20 suitably 90 secured to the base-member 6, for conveniently operating the device, although other means may be suitably improvised for that purpose. It will be observed that as above indicated when the base-member 6 is suitably actuated for instance by the child nat- 95

urally pushing against it, the figure or effigy will be vertically oscillated and at the same time the device be moved bodily along, which will have the effect, it is thought apparent, to stimulate the child to persist in 100 actuating the device and thus serve to aid the child to "stepout" or walk. It will also be understood that for the push-rods 5 herein employed there may be substituted a chain and sprocket-wheel, or a worm and 105 pinion for effecting the same end and therefore I do not restrict myself to the particular means herein shown for that purpose.

It will be observed that, in suitably actuating the bar or handle 19, the wheels 2 will 110 be rotated and the crank-shaft or axle 1, accordingly actuated together with the pitmen

or rods 5, in turn actuating the crank-shaft 4 and with it the simulated human figure 3 through the elements 11, 12, 13, 14, 15, 16 and 17. This movement of parts, while it 5 transmits a slight forwardly traveling movement to the whole structure, causes an upward and rearward movement of the figure 3, facing the child, in a leaping attitude toward, and thus drawing the attention of the 10 child. The impulse thus excited in the child will instinctively have the effect to prompt the latter to suddenly "toddle" toward the figure in an attempt to grasp it and thus aid or expedite a walking action in the child.

15

I claim—

A device of the type described, including a figure simulating a human-being, a crank-shaft, a transportable base-member, a pitman actuating said crank-shaft from said transportable base-member, supporting 20 means for said crank-shaft from said base-member, a plurality of U-shaped interjointed frame-like members, adapted to coöperate with the head, hands and feet of said figure and mechanism coöperating with said figure 25 for actuating the same.

In testimony whereof I affix my signature.

WALTER W. WHITE 3. W.
